ABSTRACT: A device for driving anchoring members is formed of a casing enclosing a barrel and a gripping sleeve and cap member slidably mounted on the exterior of the casing. The gripping sleeve and cap member can be operatively engaged with the barrel to move as a unit relative to the casing. A lever is pivotally mounted on the casing and is movably positionable into alignment in front of the bore in the barrel and a slot in the barrel wall for moving an anchoring member and a hammer piston into the firing position within the barrel.

DEVICE FOR DRIVING ANCHORING MEMBERS

SUMMARY OF THE INVENTION

This invention is directed to an anchoring member driving mechanism and, more particularly, it is concerned with a member attached to the mechanism for moving anchoring members and the hammer piston of the mechanism from the nozzle end to the opposite end of the bore in the mechanism.

Devices used for driving anchoring members, such as bolts and the like, into hard receiving material by means of an explosive charge contained in a cartridge generally employ a hammer piston which is freely displaceable axially through the barrel of the device. In the firing position, the rear end of the piston is disposed against a cartridge bearing end of the barrel and its forward end supports an anchoring member. The present invention is primarily concerned with the manner in which the anchoring member and the piston are placed in the firing position within the barrel.

In devices for driving anchoring members it has been known to use a separate rod, not attached to the device, for moving the anchoring member and the hammer piston through the barrel into the firing position.

Where a separate loading rod is employed it has the disadvantage that after the loading operation is completed, it must be set aside and it is quite possible that it may become lost or displaced. Further, when operating the device in locations spaced above the ground, such as on scaffolds, the loading rod may fall and be lost or be difficult to recover. Moreover, the requirement for handling the rod during the loading operations and then placing it in some other position involves a certain amount of lost effort and tends to reduce the efficiency of anchoring member inserting operations.

Accordingly, it is the primary object of the present invention to overcome the disadvantages experienced where a separate loading rod is employed and to afford a device incorporating means for loading the anchoring member and hammer piston into the firing position.

Another object of the invention is to provide a mechanism which will position the anchoring member and the hammer piston in the firing position in the barrel and then be removable from the barrel so as not to interfere or impede the operation of inserting the anchoring mechanism into a receiving material.

Moreover, another object of the invention is to provide a device which is simple in arrangement, effective in operation and easy to handle.

Therefore, in the present invention, a lever is pivotally mounted on the casing of the device and is movable between a first position for loading the anchoring members and hammer piston into the firing position and a second position where the lever is moved out of alignment with the barrel of the device. Further, a gripping sleeve and cap member are connected together and are arranged on the casing to engage the barrel for movement as a unit relative to the casing. An arm or lever is pivotally fixed to the casing and when the barrel is displaced axially in the firing direction the lever enters the barrel and guides the anchoring mechanism and the hammer piston into the firing position.

For effecting the passage of the lever relative to the barrel, a slot is provided in the barrel through which the lever slides in moving the anchoring member and the hammer piston into the firing position. In its first position, the lever is aligned with the slot and with the bore through the barrel of the device. When it is moved into its second position, the lever is displaced out of alignment with the bore and the slot so that it does not interfere with the firing of the anchoring members.

The various features of novelty which characterize the invention are pointed out with particularity in the claims annexed to and forming a part of this specification. For a better understanding of the invention, its operating advantages and specific objects attained by its use, reference should be had to the accompanying drawings and descriptive matter in which there is illustrated and described a preferred embodiment of the invention.

BRIEF DESCRIPTION OF THE DRAWINGS

In the drawings:

FIG. 1 is a view, partly in section, taken along the axis of the forward end of an anchoring member driving device embodying the present invention;

FIG. 2 is an end view of the device shown in FIG. 1 taken in the direction of the arrow II in FIG. 1; and

FIG. 3 is a detail view of a groove formed in the nozzle end of the barrel of the device shown in FIG. 1.

DETAILED DESCRIPTION OF THE PREFERRED EMBODIMENT

In the drawing the forward end of a device for driving anchoring members into a receiving material is shown comprised of an axially extending casing 1, the left end of which in FIG. 1 designates the discharge or nozzle end of the device. Disposed about the outer surface of the casing 1 is a gripping sleeve 2 to which a transversely arranged protective cap 3 is secured by means of screws 8. The sleeve 2 and cap 3 are connected together for rotational and axial movement relative to the casing. At the nozzle end of the casing on a part thereof which projects through an opening in the cap 3, an L-shaped lever or arm 4 is pivotally attached to it and the lever is movable between a first position, as shown in FIG. 1, and a second position, as shown in FIG. 2. The longer leg of the L-shaped lever is attached to the casing and its shorter leg extends substantially perpendicularly to the longer leg at its end remote from its point of attachment to the casing. The pivot axis of the arm 4 extends through the wall of the casing perpendicularly to the axis of the casing. Secured to the face of the cap 3 by means of a screw 11 is a cam member 5.

Disposed within the casing is a barrel 6 having a bore 6a which extends between a nozzle end 6b and a cartridge bearing end 6c. The barrel 6 is slidably positionable in the axial direction through the casing 1. The inner surface of the casing 1 and the outer surface of the barrel 6 are shaped to provide an annular open space 1b closed at the opposite ends thereof by an annularly extending shoulder 1a on the casing and an annularly extending shoulder 6d on the barrel. The length of the space 1b determines the extent of movement of the barrel in the axial direction with the shoulder 1a on the casing forming a stop for the shoulder 6d on the barrel.

A hammer piston 7 is located in the barrel, and as shown in FIG. 1 it is located in the firing position at the cartridge end of the barrel. For firing anchoring members from the bore of the barrel, the hammer piston is freely movable through the barrel. At its forward end 13, facing in the direction of the nozzle end 6b of the barrel, the hammer piston is arranged to receive an anchoring member, such as the bolt 12 shown in FIG. 1, the head of which seats within the end 13 of the hammer piston. In addition to the support provided by the hammer piston 7, the bolt is also supported by a washer 14 disposed concentrically about the shank of the bolt 12 and extending radially outwardly into contact with the surface of the bore.

As viewed in FIG. 1, the upper portion of the barrel 6 contains a J-shaped groove while the lower part of the barrel contains an axially extending slot 16 which is open at the nozzle end of the barrel and extends rearwardly through the wall of the barrel toward its cartridge end. The J-shaped groove 15 is formed of two parallel and spaced groove components 15a, 15b joined by a transverse groove component 15c spaced inwardly from the nozzle end of the barrel. The groove component 15a is open at the nozzle end of the barrel while the groove component 15b is closed and terminates inwardly from the nozzle end of the barrel.

In operating the device, the hammer piston 7 is located at the nozzle end of the barrel and a bolt 12 is inserted into the bore with its head fitted within the end 13 of the piston 7. Initially, the bolt is inserted a sufficient distance into the barrel so that the washer 14 rests against the surface of the bore 6a. Next, the gripping sleeve 2 and the cap 3 are rotated in the direction of the arrow III shown in FIG. 2 so that the cam 5 is moved out of the groove component 15a through the groove

component 15c into the groove component 15b. In this position, the gripping sleeve can be moved forwardly and the cam 5 engages the barrel 6 within the groove component 15b for moving the barrel forwardly in the firing direction relative to the casing 1. When the bolt is inserted into the barrel, the lever 4 is in its second position as indicated in FIG. 2, that is, extending transversely to the axis of the bore and disposed out of alignment with the bore and the barrel. In the second position the lever or arm 4 extends laterally outwardly from the casing across the forward face of the cap 3, that is, the face oriented toward the nozzle end 6b of the barrel. As the gripping sleeve and cap member are moved forwardly, along the casing, the forward face of the cap 3 pivots the lever 4 about its axis in the casing from the second position, see FIG. 2, into the first position, see FIG. 1, where the upstanding leg of the L-shaped lever is aligned with the bore 6a and the slot 16 through the barrel. As the interengaged gripping sleeve, cap member and the barrel continue to be moved forwardly, the upstanding shorter leg of the lever 4 enters the slot and the bore in the barrel and engages the face of the washer 14 and moves the bolt 12 and the hammer piston 7 to the opposite end of the barrel since the lever 4 is secured to the casing which is in a stationary position relative to the movement of the gripping sleeve and barrel.

After the bolt 12 and the hammer piston 7 are disposed in the firing position, the sleeve 2 and cap 3 along with the barrel 6 are returned in the direction of the cartridge end of the barrel on the casing, again assuming the position shown in FIG. 1. After the rearward motion is completed, by effecting a rotational movement between the sleeve and the casing in the opposite direction to the arrow III of FIG. 2, the cam 5 is moved from the groove component 15b through the groove component 15c back into the groove component 15a and the device is loaded and ready to drive the bolt into a receiving material.

Further, with the cap and sleeve returned to the position shown in FIG. 1, the lever 4 is returned to the position in FIG. 2 where it is held in position across the forward face of the cap so that it does not interfere with the firing of the device.

I claim:

1. An anchoring member nozzle mechanism comprising a casing, a barrel disposed within said casing and forming an axially extending bore therethrough having a nozzle end and an oppositely disposed cartridge end and said bore arranged to receive an anchoring member inserted into its nozzle end, said barrel having a slot extending in the axial direction from the nozzle end thereof toward the cartridge end and transverse to the axial direction said slot extends from the outer surface of said barrel to the bore therethrough, said barrel being movable relative to said casing in the axial direction of its bore, an arm pivotally fixed to said casing at the end thereof located adjacent to the nozzle end of said barrel, said arm arranged to be pivoted between a first position aligned with said bore and slot in said barrel and a second position pivotally displaced out of alignment with said bore and said barrel, first means cooperating with said casing for moving said arm between its first and second positions, and second means cooperating with said first means for moving said barrel axially relative to said casing and arm so that its nozzle end is projected outwardly from said casing whereby with said arm in the first position as

said barrel is moved axially in the direction of its nozzle end said arm extends through said slot into said bore in said barrel and is arranged to displace an anchoring member located therein from the nozzle end toward the cartridge end of the bore.

2. An anchoring member driving mechanism, as set forth in claim 1, wherein said first means comprises a gripping sleeve disposed about and movably mounted on said casing radially outwardly from said barrel, a cap member extending transversely of and secured to said sleeve at its end adjacent the nozzle end of said barrel, the nozzle end of said barrel extending outwardly from the adjacent end of said casing, said cap having a central opening therein disposed about the outer surface of said barrel, and said second means comprises a cam attached to said cap member and selectively engageable with said barrel for displacing said barrel relative to said casing.

3. An anchoring member driving mechanism, as set forth in claim 2, wherein a J-shaped groove is formed in the exterior surface of said barrel and is composed of a pair of groove components spaced apart and extending in the axial direction of said barrel with another groove component interconnecting said axially extending groove components at a location spaced from the nozzle end of said barrel, one of said pair of groove components being longer than the other and being open ended at the nozzle end of said barrel and extending therefrom toward the other end of said barrel to said interconnecting groove component, and the other of said pair of groove components extending from said interconnecting groove component toward the nozzle end of said barrel and terminating at a location spaced from the nozzle end of said barrel so that it forms a stop surface against which said cam acts for axially displacing said barrel relative to said casing.

4. An anchoring member driving mechanism, as set forth in claim 1, wherein the inner surface of said casing and the outer surface of said barrel are shaped to provide an axially extending annular open space therebetween closed at one of its ends by a radially outwardly extending shoulder on said barrel and at its other end by a radially inwardly extending shoulder on said casing whereby the axial movement of said barrel outwardly from said casing is limited to the length of said annular space in the axial direction of said barrel.

5. An anchoring member driving mechanism, as set forth in claim 1, wherein a hammer piston is disposed within and is axially movable through the bore in said barrel and is arranged to drive anchoring members outwardly from said barrel, said hammer piston is shaped at its end closer to the nozzle end of said barrel to provide a recess for receiving the end of an anchoring member and its end closer to the nozzle end is spaced inwardly from the surface of the bore within said barrel.

6. An anchoring member driving mechanism, as set forth in claim 1, wherein said arm has an L-shaped configuration having one leg thereof pivotally secured to the end of said casing and the other leg extending outwardly from said one leg at its end opposite the end pivotally secured to said casing and said other leg arranged to extend through the slot in said barrel into the bore therein when said barrel is displaced axially in a direction of its nozzle end for displacing an anchoring member within the bore toward the cartridge end thereof.
